UNITED STATES PATENT OFFICE.

GEORGE H. HILL, OF SCHENECTADY, NEW YORK, ASSIGNOR TO GENERAL ELECTRIC COMPANY, A CORPORATION OF NEW YORK.

CONTROL APPARATUS.

No. 927,465.

Specification of Letters Patent.

Patented July 6, 1909.

Continuation of application Serial No. 330,294, filed August 13, 1906. This application filed April 18, 1908.
Serial No. 427,906.

To all whom it may concern:

Be it known that I, GEORGE H. HILL, a citizen of the United States, residing at Schenectady, county of Schenectady, State 5 of New York, have invented certain new and useful Improvements in Control Apparatus, of which the following is a specification.

The present invention relates to means for 10 controlling electric motors and particularly in systems wherein it is desired to enable the operator to control the motor from any one of a plurality of stations, and the invention has for its object to provide a system 15 simple in construction and operation whereby the motor may be controlled in any desired way from a single station or from any one of a plurality of stations by simply pressing a push-button or other form of 20 small switch.

The invention will be more fully understood and its objects and advantages will more clearly appear from the following description thereof taken in connection with 25 the accompanying drawings wherein—

Figure 1 is a front elevation of a master-controller arranged in accordance with the present invention; Fig. 2 is a detail of the controller; Fig. 3 is a detail elevation taken 30 on the line 3—3 of Fig. 1; and Fig. 4 is a diagram of connections showing a motor, a motor controller, the master-controller for governing the operation of the motor controller, and a two-station push-button system 35 for governing the master-controller.

The system illustrated in the drawing is one particularly adapted for use in connection with printing presses, wherein it is highly desirable that the operator shall be 40 able to start and stop the press and run it at the low speeds while threading in and adjusting the paper, without being required to go to a central station whenever it is desired to effect a change in the operation of 45 the press. The system is also arranged so as to prevent the press from being inadvertently started or its speed accelerated after the operator has set the proper switch, thereby rendering the machinery safe to the operator 50 while examining or adjusting the mechanism or the paper.

Referring first to Fig. 4, M is a compound wound motor, the armature A and series field S of which are adapted to be shunted

across variable portions of a resistance R 55 in starting and the shunt field S' of which is adapted to be weakened or strengthened by cutting into or out of series with it sections of the resistance R¹. At B is indicated a coil by which a brake biased to the "on" 60 position is released when the motor circuit is completed. The manner in which this brake coil B is energized will be hereinafter explained. C is a controller, of the separately-actuated contact type, arranged to 65 first connect the motor armature and series field-across-variable portions of resistance R and then to short-circuit the series field and connect the armature directly across the line. These elements, of course, need not be in the 70 particular forms shown, since the motor may be of any desired type and have its acceleration and speed controlled in any desired way. K is a master-controller which directly controls the operation of the switches 75 which make up the controller C and which varies the strength of the shunt field S' by cutting into or out of series therewith the resistance R¹. The operation of this master-controller K is hereinafter fully described. 80 At 1 and 2 are control stations, at each of which is located a set of push-buttons or other switches by which the operation of the master-controller K is regulated. There may be, of course, any number of these control stations, but for the sake of simplicity I have illustrated only two. At the control stations the switches G¹ and G², which are biased to an open position, serve as starting 85 switches; switches H¹ and H², also biased to open position, serve as slowing down switches; switches I¹ and I², biased to a closed position, are for stopping the motor; and switches J¹ and J², which will remain 90 either closed or open, are safety switches, either of which when open prevents starting of the motor if the same is at rest or increasing the speed thereof if it is operating. The manner in which these switches G¹ and G², H¹ and H², I¹ and I² and J¹ and J² 95 operate will be hereinafter described. At O is shown an overload relay which serves to throw the master-controller to its "off" position, thereby opening the switches of the controller C, if at any time the current 100 in the motor circuit exceeds a certain predetermined value. The source of current supply for the armature and series field of 105

motor M is indicated at L and L¹, a suitable switch W serving to connect the motor circuits to this source. At l and l¹ is indicated a source of current supply for the control circuits of the system and for the shunt field S¹ of the motor M. It is, of course, obvious that the current both for the armature and series field circuits, and for the shunt field and control circuits might be taken from the same source if the conditions were suitable.

The mechanical construction of the master-controller is illustrated in Figs. 1, 2 and 3, and its electrical connections diagrammatically indicated in Fig. 4. This master-controller comprises a row of fixed contacts k which, during movement of the master switch, are successively connected to a fixed contact k¹, and a plurality of fixed contacts k², which during the movement of the controller, are successively connected to a fixed contact k³. The contacts k and k¹ are engaged respectively by fingers 3 and 4 electrically connected together through a blow-out coil 5 mounted as shown in Figs. 1 and 3, and arranged to blow out any arc which may form between the fingers 3 and 4 and the contacts k and k¹. Similarly, contacts k² and k³ are engaged by fingers 6 and 7 connected together through a blow-out coil 8. The fingers 3 and 4, 6 and 7 and blow-out coils 5 and 8 are carried by a yoke 9 which is moved in a vertical direction by certain electro-magnetically operated means herein-35 after described.

The operating means for the master-controller comprises an accelerating magnet D, a slowing-down magnet E and a holding or latching magnet F, all of which together with the other parts of the device are suitably secured to the back Z. These magnets control the movement of the yoke 9 which carries the contacts 3, 4, 6 and 7, said yoke being secured to a toothed rod 15 which extends upwardly and is slidably arranged in a suitable guide 16. The yoke 9 may be arranged to slide on a casing 17 within which the rod 15 moves. Arranged for movement within the accelerating magnet D is a core d which is pivotally connected at its lower end to a dog d¹ carried by and pivoted on a lever d² pivoted to the back Z at d³, as clearly shown in Figs. 1 and 2. With this arrangement energization of the coil D will cause pulling up of the core d and engagement of the dog d¹ with the teeth on the right-hand side of the rod 15, the operation of the parts being such that upward movement of the core d raises the rod 15 one tooth which is 60 equal to the distance between the contacts k.

The mechanism by which the rod 15 is held in any raised position or is allowed to drop notch-by-notch, or is permitted to fall freely under the influence of gravity, is 65 clearly illustrated in Figs. 1 and 2. This

mechanism comprises a casing 20 surrounding the rod 15, in which casing are pivoted at 21 and 22 dogs f and e which may be called, respectively, holding and slowing-down dogs. The dog f engages with the teeth on the right side of rod 15 and the dog e meshes with the teeth on the left side of said rod but the dog e is so arranged that it must always, when thrown into engagement with rod 15, engage the next tooth above that with which the dog f has meshed. Also pivoted at 22 in the casing 20 is a lever e¹, of the form shown, which has a heel e² which co-acts with the extension e³ on dog e in a manner hereinafter explained. The upper extensions of the dogs f and e¹ are connected together by links 23, one on each side of the rod 15, these links being pivoted at 24 to the lever e¹ and having sliding engagement with a pin 25 in the lever f, as clearly shown in Figs. 1 and 2. The core e⁴ of the magnet E has a lost motion connection with the lever e¹ consisting of a pin e⁵ passing through the core e⁴ and across a slot therein into which the bifurcated end of the lever e¹ extends, as clearly shown in the drawings. The extended end of the dog f is engaged by the core f¹ of the magnet F and a spring f² carried by the dog f engages a slot in the end of the core f¹ in a manner apparent from Figs. 1 and 2. A spring 26 tends to draw the dogs f and e together, but the links 23 are of such a length that but one of the dogs f or e can engage the toothed rod 15 at once. The parts just described are so proportioned as to weight and the strength of the springs 26 and f² that when magnets E and F are deenergized and their cores are in their lowermost position, as indicated in Fig. 1, both of the dogs e and f will be out of engagement with the teeth on the rod 15. In Fig. 2 the dog f is shown in engagement with the teeth on the rod 15 but this is only because the cores e⁴ and f¹ of the magnets E and F are not exerting their weights upon the ends of the lever e¹ and the dog f. Furthermore, the length of the link 23 is such that but one of the dogs e or f can be in engagement with the notched rod 15 at the same time. That is, if the dog f is in engagement with the notched rod 15 the dog e will, by the engagement of the toe e² with the extension e³, be moved out of engagement with the rod 15; or if the lever e¹ be moved in a clockwise direction, thereby allowing the dog e under the influence of the spring 26 to engage the teeth on the rod 15, the links 23 will force the dog f out of engagement with its co-operating teeth on the rod 15. Operation in this manner is facilitated by the spring connection f² between the core f¹ and the dog f and the lost motion connection between the core e⁴ and the lever e¹, as will be apparent from an inspection of Figs. 1 and 2. The core d in 130

rising is arranged to lift a rod d^4 carrying a contact disk d^5 which bridges contacts d^6 , thereby interrupting the circuit through the magnet D, as indicated in the diagram of Fig. 4. The rod d^4 is free to move upwardly but is retarded in its downward movement by means of a dash pot d^7 , or in any other suitable manner. With this arrangement the magnet D is necessarily intermittent in its operation, and, therefore, serves to operate the movable parts of the master-controller step-by-step in a manner hereinafter further explained. The magnet E is rendered intermittent in its action in the same manner as the magnet D by means of a rod e^6 which is lifted by the core e^4 and which carries a contact disk e^7 arranged to bridge fixed contacts e^8 , the rod e^6 being provided with a dash pot e^9 which retards it in its downward movement while allowing it to move freely in an upward direction. A bell crank lever 30 of the form shown is pivoted at 31 to the back Z and is arranged to be engaged by the rod 15 and moved from the position illustrated in Fig. 1 to that shown in Fig. 2. This movement of the lever 30 allows the contact disk 32 to rise under the influence of a spring 33 and bridge fixed contacts 34, thereby closing a circuit at that point for the purpose hereinafter explained. In order to provide an upper limit stop device for the rod 15 an L-shaped member 35 is arranged for vertical sliding movement upon pins 36 and 37 fixed to the back Z, said member 35 having a projection 38 upon the front face thereof which is engaged by a pin 39 projecting from the rod 15 when said rod has come within one tooth of the upper limit of its travel which is the position shown in Fig. 2. When the rod 15 is raised one notch farther the L-shaped member 35 is lifted and its toe 39 engages with and holds in its raised position the rod d^4 carrying the contact disk d^5 , thereby preventing the falling of the rod d^4 and the closing of the circuit for the magnet D after the core d has dropped. In this way further operation of the magnet D is prevented after it has raised the movable contacts of the master-controller to their uppermost position.

Referring particularly to Fig. 4, the motor and control circuits will now be traced. The controller C is made up of electro-magnetic switches 49 to 54 inclusive, of which the switches 51 to 54 have their actuating coils connected to the fixed contacts k on the master-controller by wires 51^a to 64^a inclusive. A switch 65 is arranged to control the circuit through a brake releasing coil B in a manner hereinafter described. The points between the sections of resistance R^1 are connected to the fixed contacts L^2 on the controller through wires 66 to 72 inclusive. Fixed contact L^3 on the master-controller is connected to the source l through wires 73

and 74 and one terminal of the shunt field S^1 is connected to the source l^1 through wire 75. It is clear, therefore, that the fingers 6 and 7 on the master-controller serve, by engaging fixed contacts k^2 and k^3 during their movement, to complete the circuit through the shunt field S^1 of the motor M and to vary the amount of resistance in this shunt field circuit thereby adjusting the strength of this field. It is clear also that the fingers 3 and 4 during their movement connect the fixed contacts k^4 successively to the contacts k which are connected by wires 51^a to 64^a inclusive to the actuating coils of the various switches making up the motor controller C. The actuating circuits for all three of the master-controller operating magnets D, E and F derive their current from the source l through wires 74 and 76, contacts of overload relay O, wire 77, through contacts of stopping switches I^1 and I^2 in series, to wire 78. From wire 78, through wires 79, 80 and 81 current is carried to the fixed contact k^4 and it is, therefore, apparent that this supply circuit for the switches which make up the controller C can at any time be interrupted by opening either of the switches I^1 or I^2 . From the wire 78, through the safety switches J^1 and J^2 in series, and then in parallel through contacts closed by either of switches, G^1 or G^2 a circuit may be traced to wire 82 which leads through the contacts d^6 and d^5 to the accelerating magnet D and thence through wires 83 and 84 to the source l^1 . Also from the wire 78 circuits may be traced, in parallel through other contacts closed by the starting switches G^1 and G^2 , to the wire 85, thence through wire 86, through the holding magnet F, and wires 83 and 84 to the source l^1 . Still another circuit passes from the wire 78, in parallel through the slowing-down switches H^1 and H^2 , to wire 87 and thence through contacts e^8 and e^7 , through the slowing-down magnet E, and wires 83 and 84 to the source l^1 . The contact disk 32, which is arranged to bridge the contacts 34 as soon as the master switch has raised to the first or second notch, connects wires 79 and 85 together and thus completes a circuit for the holding magnet F independent of the starting switches G^1 and G^2 . In the arrangement just described wire 82 may be called the "accelerating wire," wire 87 the "slowing-down wire," wire 85 the "initial holding wire" and wire 79 the "permanent holding wire." It is to be observed that with this arrangement when either of the safety switches J^1 or J^2 are open the starting and accelerating switches G^1 and G^2 are ineffective, but the slowing-down switches H^1 and H^2 and the stopping switches I^1 and I^2 will still perform their functions; that opening of either stopping switches I^1 or I^2 immediately interrupts the circuits through all of the magnets D, E and F and through the

operating coils of the switches which make up the controller C; that closing of either slowing-down switches H^1 or H^2 energizes the slowing-down magnet E; and that closing of either starting or accelerating switches G^1 or G^2 , provided the safety switches J^1 and J^2 are closed (and, of course, provided the slowing-down switches H^1 and H^2 and stopping switches I^1 and I^2 are in their normal positions) will cause the energization of the accelerating magnet D and, consequently, the operation of the master-controller step-by-step in an upward direction.

The mode of operation of my system of control is as follows: As illustrated in Fig. 4, the motor is supposed to be at rest, the brake applied, the master-controller K and the motor controller C in their "off" positions, the safety switches J^1 and J^2 closed, and the starting and accelerating switches G^1 and G^2 , the slowing-down switches H^1 and H^2 and the stopping switches I^1 and I^2 in their normal positions. If now the switch G^1 is closed the accelerating magnet D and the holding magnet F are energized. The master-controller, therefore, commences to operate and the yoke 9 carrying fingers 3, 4, 6 and 7 rises. As soon as the fingers 6 and 7 engage the fixed contacts k^2 and k^3 the circuit through the shunt field S^1 is completed, as hereinbefore explained. As soon as the finger 4 engages with the fixed contact k^1 and the finger 3 engages with the lowermost fixed contact k a circuit is completed from the source l , through wires 74, 76, contacts of overload relay O, wire 77, switches I^2 and I^1 , wires 78, 79, 80 and 81, contact k^1 , finger 4, blow-out coil 5, finger 3, contact k , wire 51^a, actuating coil of switch 51, wire 90, actuating coil of switch 50, wire 91, actuating coil of switch 49, actuating coil of switch 65, wires 92 and 84 to the source l^1 . Switches 51, 50, 49 and 65, are, therefore, closed. Closing of switch 65 completes a circuit from wire 80, through wire 93, releasing coil B of the brake, switch 65 and wires 92 and 84 to the source l^1 , thereby energizing the brake coil B and releasing the brake. Closing of switches 51, 50 and 49 connects all of the resistance R across the source L , L^1 and connects the armature A and series field S of the motor M in shunt to the portion r of the resistance R. The motor will then be excited with compound wound fields. If the switch G^1 be held closed the movable member of the master-controller K will continue to rise step-by-step and the wires 52^a, 53^a, 54^a, etc., will be successively energized. As soon as the movable member of the master-controller has risen sufficiently (that is, one or two notches) to cause the closing of the contacts 32 and 34, the holding magnet F will be rendered independent of the switch G^1 , and if this switch is released at any time the master-controller will stop in its movement and

be held by the holding magnet F at the position in which it then is. Successive energization of the wires 52^a to 63^a inclusive completes the circuit successively through the actuating coils of the switches 52 to 64 inclusive, though interlocks 49^a closed by the closing of the switch 49, to wire 90, thence through the actuating coil of the switch 50, wire 91, actuating coil of the switch 49, actuating coil of the switch 65, and through the path previously traced to the source l^1 . Closing of the switches 51 to 63 inclusive results in connecting the motor armature A and series field S in shunt to greater and greater amounts of the resistance R until they are finally connected in shunt to all of this resistance R except the section r^1 . During operation of these switches 51 to 63 inclusive the switches 49, 50 and 65 remain closed since the current for each of the first named switches passes through the actuating coils of the latter. When, however, the wire 64^a is energized current flows through the actuating coil of the switch 64, interlocks 63^b closed by the switch 63, directly to wire 91, and thence actuating coils of switches 49 and 65 and the path previously traced, the switch 64 being closed, which in closing completes a circuit through the interlocks 64^b in shunt to the circuit through the interlocks 63^b. As soon, therefore, as the wire 63^a is deenergized by the finger 3 passing off the contact k connected to said wire, the switches 63 and 50 open. The motor armature A is then connected directly across the source L , L^1 and the resistance R is disconnected from said source. If the movable element of the master-controller is moved still further the finger 6 passes beyond the lowermost contact k^2 and engages successively with the smaller contacts k^2 which are connected by wires 67 to 72 inclusive to points between the sections of the resistance R^1 , and the shunt field S^1 is weakened by including in its circuit the resistance R^1 . When the finger 6 has reached the uppermost contact k^2 further upward movement of the movable contact member is prevented by the lifting of the L-shaped member 35 by the pin 39 and the consequent interruption of the control circuit for magnet D as hereinbefore explained. The movement of the movable element of the master-controller results, therefore, in increasing the speed of the motor step-by-step, first by shunting its armature and series field around a greater and greater amount of resistance connected across the source, then by cutting out the series field altogether and connecting the armature directly to said source, the resistance being at the same time disconnected, and finally by weakening the shunt field by interposing an increasing amount of resistance in the shunt field circuit. At any time during this operation the movement of the master-controller may be stopped by simply

allowing the switch G^1 to open; or the master-controller may be returned step-by-step for any number of steps toward its "off" position by closing either of the slowing-down switches H^1 or H^2 ; or the motor may be instantaneously disconnected from the source by depressing either of the stopping switches I^1 or I^2 , an operation which interrupts the control circuit for the switches of controller 10 C and at the same time allows the master switch to drop unimpeded to its "off" position; or the motor after being brought to a certain speed may be prevented from being accelerated to any higher speed by opening 15 either of the safety switches J^1 or J^2 .

Although I have illustrated but one form of embodiment of my invention, I do not desire to be limited to the particular form shown since in its broader aspects the present 20 invention may be incorporated in various forms, as indicated by the terms of the appended claims.

What I claim as new and desire to secure by Letters Patent of the United States, is,—

25 1. In a controller, a movable contact member having a tendency to assume its "off" position, an electro-magnet for holding said member out of the "off" position, an electro-magnet for moving said member step-by-step from the "off" position, an electro-magnet coöperating with the first electro-magnet to return the said member to the "off" position step-by-step, means associated with each of the two last mentioned 30 electro-magnets for interrupting the circuit of each after a step of movement of said contact member has been effected thereby, and means for controlling the electro-magnets to cause the said member to return to 40 the "off" position by a continuous movement.

2. In a controller, a movable contact member having a tendency to return to the "off" position, a holding pawl for said member, an electro-magnet arranged to move said member a step away from the "off" position whenever it is energized, a second electro-magnet coöperating with said pawl to cause 45 said member to return a step toward the "off" position when the electro-magnet is energized, means for closing circuits through said electro-magnets, and means associated with each electro-magnet for interrupting its circuit after each step of movement of the 50 said member has been effected thereby.

3. In a controller, a movable contact member tending to assume its "off" position, a toothed element connected thereto, a holding pawl coöperating with said toothed element, an electro-magnet connected to said pawl, a 55 second electro-magnet having a movable core, a pawl carried by said core and arranged to engage said toothed element to operate the said controller member step-by-step away from the "off" position, a third

electro-magnet having a movable core, a pawl operatively connected to said latter core and to the holding pawl for releasing the controller member step-by-step, means associated with each of the second and third 70 mentioned electro-magnets for interrupting the circuit of each after a step of movement of said contact member has been effected thereby, and switches for controlling said electro-magnets.

4. In a controller, stationary contacts, a movable contact member coöperating therewith and biased to an "off" position, a notching-up magnet for moving said member step-by-step in an "on" direction, a holding magnet for holding said member in any "on" position, a notching-down magnet for allowing said member to move step-by-step in the "off" direction, control circuits for said magnets, station switches for closing 80 said control circuits, means controlled by said notching-up magnet for automatically and repeatedly opening and closing contacts in its control circuit thereby insuring repeated operation of said notching-up magnet as 90 long as one of its station switches is closed, and means controlled by said notching-down magnet for automatically and repeatedly opening and closing contacts in its control circuit thereby insuring repeated operation 95 of said notching-down magnet as long as one of its station switches is closed.

5. In a controller, stationary contacts, a movable contact member coöperating therewith and biased to an "off" position, a notching-up magnet for moving said contact member step-by-step in an "on" direction, a holding magnet for holding said member in any "on" position, a notching-down magnet coöperating with said holding magnet to 100 permit the movable contact member to return step-by-step in an "off" direction, control circuits for said magnets, a plurality of control stations, switches at said control stations by which said control circuits may 110 be controlled, means for causing repeated operation of said notching-up magnet while its control circuit is closed at a control station, means for causing repeated operation of said notching-down magnet while its control circuit is closed at a control station, said notching-up, notching-down and holding magnets being so arranged that when de-energized the movable contact member is 115 free to move uninterruptedly toward its 120 "off" position.

6. In a controller, stationary contacts, a movable contact member coöperating therewith and biased to an "off" position, electro-magnetically operated notching-up mechanism arranged to move said contact member step-by-step in an "on" direction, electro-magnetically operated holding and notching-down mechanism arranged to hold said contact member in any "on" position or to per- 125 130

- mit it to move step-by-step in an "off" direction, control circuits for said mechanisms, a plurality of control stations having switches for controlling said control circuits, 5 said notching-up mechanism being arranged to operate repeatedly as long as its control circuit is closed at a control station, and said notching-down and holding mechanism being arranged to allow said contact member 10 to move step-by-step in an "off" direction as long as the control circuits for said mechanism are closed at one of the control stations.
7. In a controller, stationary contacts, a 15 movable contact member coöperating therewith and biased to an "off" position, electro-magnetically operated notching-up mechanism arranged to move said contact member step-by-step in an "on" direction, electro- 20 magnetically operated holding and notching-down mechanism arranged to hold said contact member in any "on" position or to permit it to move step-by-step in an "off" direction, control circuits for said mechanisms, 25 a plurality of distant control stations, a switch at each station for controlling the control circuit for said notching-up mechanism, a second switch at each control station for controlling the control circuit for 30 said holding and notching-down mechanism, a third switch at each station for interrupting the control circuits to all of said electro-magnetically operating mechanisms, and a fourth switch at each station for rendering 35 the first named switch at all stations ineffective.
8. In a controller, stationary contacts, a 40 movable contact member coöperating therewith and biased to an "off" position, electro- magnetically operated notching-up mechanism arranged to move said contact member step-by-step in an "on" direction, electro- 45 magnetically operated holding and notching-down mechanism arranged to hold said contact member in any "on" position or to
- permit it to move step-by-step in an "off" direction, means for rendering said notching-up mechanism inoperative when said movable contact member has reached its full "on" position, control circuits for said mechanisms, and a plurality of control stations having switches for controlling said control circuits and thereby the operation of said controller. 50
9. In a system of control, a motor, and a controller for said motor including a switch or push-button to gradually accelerate the motor, a switch or push-button to gradually retard the motor, a switch or push-button to stop the motor quickly, and a switch or a push-button for preventing acceleration. 55
10. In a system of control, a controller arranged to be operated electrically from a distance, a plurality of distant control stations, a switch at each control station for effecting 60 movement of the controller step-by-step in the "on" direction, a second switch at each control station for effecting movement of the controller step-by-step in the "off" direction, a third switch at each station for causing the 65 uninterrupted return of the controller to the "off" position, and a fourth switch at each station for rendering the first named switch at all stations ineffective. 70
11. In a system of control, a motor, a 75 motor controller, a master-controller for governing the operation of said motor controller, and electro-magnetic actuating and controlling means for said master-controller, including switches or push-buttons which 80 respectively cause the master-controller to gradually accelerate and retard the motor, and a switch for causing the master-controller to operate to stop the motor quickly. 85
- In witness whereof, I have hereunto set my hand this 16th day of April, 1908.
- GEORGE H. HILL.
